UNITED STATES PATENT OFFICE

GEORGE A. REYNOLDS, OF LOS ANGELES, CALIFORNIA

ROCK CRUSHER AND SEPARATOR

Application filed October 25, 1930. Serial No. 491,241.

This invention relates generally to the swing hammer impact type of rock crushers or pulverizers.

The apparatus of this character consists of a plurality of hammers pivotally mounted on pins extending between disks secured to a shaft, the shaft being rotated at sufficient speed to cause the hammers to assume a radial position by centrifugal force, and deliver a crushing blow on rock or other material fed upon a breaker plate.

It is necessary to adjust the relative position of the hammers to the breaker plate according to the material being handled, also to readjust the position of the hammers when they become worn.

In order to make these adjustments with the apparatus now in use it is necessary to remove the cover of the housing, then remove the pivot pins and hammers thereon and place them in other openings in the disks according to the adjustment required, for example, when the hammers become worn, the pins are placed in openings nearer the rim of the disks. This procedure not only requires a considerable amount of time and labor, but it is not possible to obtain an accurate adjustment.

It is, therefore, an object of the present invention to provide a crusher of the character stated in which the shaft carrying the disks and hammers is slidably mounted so that the relative distance between the path traversed by the faces of the hammers and the breaker plate may be adjusted without disassembling any part of the crusher.

Another object of this invention is to provide a crusher of the character stated in which a breaker plate of square shape is mounted in such a manner that after one crushing surface has become worn, the plate may be turned to a position presenting a new crushing face and so on until all four sides have become worn down, thereby permitting much longer use of the plate than has heretofore been possible.

A further object of the invention is to provide a crusher constructed in such a manner that it will function as a separator or a classifier. With the above object in view the disks

and hammers are provided with fan blades which serve to induce a current of air through the housing which passes therefrom into a horizontally disposed conduit secured to the housing and provided with a plurality of outlets, the finely divided particles of the material (when liberated by crushing) being picked up and carried by the air current into the conduit wherein they settle throughout the length thereof according to the various degrees of fineness and drop through the outlets into suitable receptacles placed therebelow. The volume of air being controlled according to the character of the material handled by intermittently operated gates, shutters or the like, alternately opening and closing air admission openings formed in the housing.

Other objects and advantages will be apparent from the following description, reference being had to the accompanying drawings, in which

Fig. 1 is a side elevation of the apparatus according to the invention.

Fig. 2 is a vertical cross section taken on line 2—2 of Fig. 1.

Fig. 3 is a transverse horizontal section taken through the apparatus.

Fig. 4 is a fragmentary detail section taken on line 4—4 of Fig. 2.

Fig. 5 is a side elevation of a modified form in which the shaft carrying the hammers is vertically adjustable, parts being broken away and shown in section.

Fig. 6 is a top plan view taken in the direction indicated by the arrows 6 of Fig. 5.

Referring more specifically to the drawings, 10 designates a housing preferably formed of cast iron comprising side walls 11, an end wall 12, and a cover 14, the cover consisting of a circular top 16 disposed between side plates 18 removably secured to the side walls by bolts or the like 19 extending through openings in flanges 20 and 22 formed on the side members and walls respectively.

Formed in the lower portion of the housing is a grate or grizzly 20 consisting of a plurality of bars 23, the opposite ends of which extend into annular recesses 24 formed in the side walls 11. It being understood that the

number of bars and the space therebetween may be varied according to the character of the material handled.

Extending through the housing and elongated openings 25 formed in the side walls is a shaft 26 upon which is mounted a plurality of disks 28, the disks being held against rotation thereon by keys 29, disposed in usual key seats formed in the shaft and hubs 30 of said disks.

Pivots mounted on pins 32 extending through aligned openings formed in the disks are hammers 34 which serve to crush rock or other material fed into the housing upon a breaker plate 36.

An important feature of this invention resides in means for adjusting the relative position between the path traversed by the faces of the hammers and the breaker plate, this is accomplished by slidably mounting the bearing 38 of the shaft 26. The bottom faces 39 of said bearings engage the upper surfaces of lateral flanges or supports 40 preferably formed integral with the side walls 12 of the housings, and are held in adjusted position by bolts 41 and nuts 42, the bolts extending through slots 43 formed in the supports.

Adjusting screws 44 are mounted in threaded openings in upstanding lugs 46 formed on each end of the supports 40 and engage the end faces 48 of the bearings.

From the construction it will be seen that by loosening the nuts 42 and turning the adjusting screws 44 a very quick and accurate adjustment between the hammers and plates may be obtained, also that it is not necessary to disassemble any part of the apparatus.

Breaker plate 36 is of square shape, and is mounted in a corresponding recess 52 formed in the end wall 14, and is retained in place by a tapered wedge or key 53 disposed in an opening in a lug 54 formed on the underside, and in the center of said plate, the lug projecting through an opening 55 in the end wall 14.

Due to the square shape and mounting of the breaker plate, it will be seen that after it has become worn across one end (i. e., the nearest to the path traversed by the hammers) it may be turned so that a new surface will be presented and so on until all four edges are worn down, thus permitting much longer use than is possible with the usual shape and mounting of these plates.

The apparatus is arranged to classify or separate the material as it is crushed. This is accomplished by providing the disks and hammers with fan blades or vanes indicated at 60 and 61 respectively, which induce a current of air through the housing, the current of air picks up and carries with it the finely divided particles as the material is crushed. The air current thus produced passes from the housing into a conduit 62 provided with a plurality of discharge openings indicated

at 64, 65 and 66, the conduit being secured to the curved top 16 of the housing by a long radius elbow 63 in register with an opening 68 formed therein. The conduit is of sufficient length to permit settling of the material, and is supported at a plurality of points throughout its length by standards or the like indicated at 67.

Air is admitted to the housing through the openings 25, the passage of the air therethrough being controlled by intermittently operated gates 70 alternately opening and closing said openings, and is arranged as follows:

Frames designated at 72 are secured by cap screws or the like 73 to the inner faces of the bearings 38, quadrants 74 having arms 76 and 77, and hangers 78 are pivotally mounted on pins 80 projecting from the frame. The gates are connected by pins 81 to the arms 76 of the quadrants 74, and by pins 82 to the hangers 78, the hangers 78 being provided to support the outer ends of the gates when in open position.

The arms 77 of the quadrants have bifurcated ends 84 which engage the outer ends of pins 85 projecting from blocks 86 formed on rods 87 slidably mounted in guide members 88 secured to the frames.

Rotatably mounted in bearings 84 secured to upper ends of the frames is a shaft 90, the shaft having eccentrics 91 thereon engaged by straps 92 which in turn are connected to the pins 85 on the blocks. A sprocket 94 is secured to the shaft, and is adapted to be connected by a chain (not shown) to any suitable source of power for transmitting rotation to said shaft.

It will be understood that means other than the above described may be employed to operate said gates.

Referring more specifically to Fig. 3, a gate designated at 100 is provided to regulate the amount of material entering the apparatus. The gate is secured to a shaft 101 mounted in bearings 102 carried by a cross bar 103 extending between the side walls 12 of the housing, the gate is held in adjusted position by an arm 104 having a clamping bolt 105 extending through an arcuate slot 106 formed in a bracket 108 carried by one of the bearings 102.

In crushing certain classes of material it may be more desirable to make the adjustment of the hammers vertically rather than horizontally; such adjustment is provided for by the construction shown in Figs. 5 and 6, arranged as follows:

Vertically disposed flanges 110 formed integral with or secured to the side walls 11 are engaged by flanges 114 of members 115 upon which the shaft bearing 116 is mounted. The member is held in place by bolts 117 extending through slots 111 formed in

the flanges 110, and openings in the flanges 114.

In making an adjustment, a jack designated at 118 is preferably employed, the jack being placed under the member 115 with its screw head engaging the underside of the cross bar 119 of said member 115, it being understood that during making such adjustment the nuts are loosened sufficiently to permit movement of the member 115.

Operation of the improved crushing and separating apparatus is as follows:

The shaft 26 is rotated in the direction indicated by the arrow A, material is fed into the housing through the opening 13, and passes under the gate onto the breaker plate 36 whereon it is crushed by impact with the hammers. The current of air induced by the fan blades 60 and 61 picks up the finely divided particles of the material and carries them with it into the conduit 62 wherein they settle on the bottom throughout the length thereof, the coarser or heaviest particles drop through the outlet 64, the medium through the outlet 65, and the lighter or fine product passes through the outlet 66.

The volume of air admitted is regulated by movement of the gates 70, the action of which also causes intermittent blasts of air which in turn aids settling and separation of the material in the conduit. In handling material which may be reduced to powder a plate indicated at P may be placed over the grate as shown in Fig. 3.

I claim:

1. An apparatus of the character described comprising a housing, a shaft extending through said housing, bearings rotatably supporting said shaft at each end thereof, a plurality of disks secured to said shaft, a plurality of hammers pivotally mounted on pins extending between said disks, a horizontally disposed conduit having a plurality of outlets connected to said housings with one end thereof in register with an opening formed in said housing, each of said disks and hammers having a plurality of blades formed thereon for inducing a current of air through said housing and conduit, and means for controlling the current of air induced by the fan blades on said disks and hammers.

2. An apparatus of the character described comprising a housing, a shaft extending through said housing, a plurality of disks having fan blades formed thereon mounted on said shaft, a plurality of pins extending between said disks, hammers mounted on each of said pins, a conduit having a plurality of openings formed therein secured to said housing, and means for controlling the current of air induced by the fan blades on said disks and hammers during rotation of said shaft.

3. An apparatus of the character described comprising in combination, a housing, a horizontally disposed conduit having one end

thereof communicating with an opening formed in the top wall of said housing and provided with a plurality of outlets, a shaft rotatably mounted in said housing and extending through elongated openings formed in the side walls thereof, a plurality of disks having fan blades thereon mounted on said shaft, a plurality of hammers pivotally mounted between said disks, pairs of gates engaging the side walls of said housing and closing the openings through which said shaft extends, and means for actuating said gates, whereby the openings in said housing will be alternately opened and closed.

4. An apparatus of the character described comprising in combination, a housing, a horizontally disposed conduit having one end thereof communicating with an opening formed in the top wall of said housing and provided with a plurality of outlets, a shaft extending through elongated openings formed in the side walls of said housing, a plurality of hammers having fan blades thereon pivotally mounted on said shaft, bearings carried by said housing engaging each end of said shaft, vertically disposed frames mounted on said bearings, a pair of gates engaging each side of said housing and closing the openings therein, hangers pivotally mounted on said frames and connected to said gates, quadrants pivotally mounted on said frames and connected to said gates, and means carried by said frames operatively connected to said quadrants for actuating said gates, whereby intermittent blasts of air will be induced through said housing and conduit during rotation of the shaft and hammers.

In testimony whereof I affix my signature.
